UNITED STATES PATENT OFFICE.

ROSCOE W. STEPHENS, OF PASADENA, CALIFORNIA.

DRILLING-RIG.

1,106,900.

Specification of Letters Patent. Patented Aug. 11, 1914.

Application filed June 12, 1913. Serial No. 774,384.

To all whom it may concern:

Be it known that I, ROSCOE W. STEPHENS, a citizen of the United States, residing at Pasadena, in the county of Los Angeles and State of California, have invented a new and useful Drilling-Rig, of which the following is a specification.

This invention relates to drilling rigs embodying a rotary drilling means, either alone or in combination with a standard rig, and the main object of the invention is to provide means for driving the rotary drilling means directly from the engine, without the interposition of the usual countershaft, chains and bevel gears.

A further object of the invention is to simplify the driving mechanism in a drilling rig.

Other objects of the invention will appear hereinafter.

The accompanying drawings illustrate an embodiment of the invention, and referring thereto: Figure 1 is a side elevation of a portion of the drilling rig. Fig. 2 is a plan view of the parts shown in Fig. 1. Fig. 3 is a plan view of the rotary table for the drilling rig. Fig. 4 is a vertical section on line x^4-x^1 in Fig. 3. Fig. 5 is a vertical section of the driving means on the engine shaft. Fig. 6 is a section on line x^6-x^5 in Fig. 5.

Referring to Figs. 1 and 2, showing the application of the invention to a combination rotary and standard drilling rig, the derrick 1 is provided with a floor 2 on which is mounted, on suitable supports, a rotary table 3 for use in rotary drilling, said table being provided with the usual means, for example, a chuck 5 for engaging with the rod, pipe or operating means 6 which carries and operates the rotary drilling tool. The engine 7 is mounted at one side of the derrick and is connected to operate the rotary table 3 by a direct rope belt connection in the following manner: A driving wheel 8 is mounted on the shaft 9 of said engine 7 and a clutch 11 is provided on said shaft 9 for clutching the wheel 8 to the shaft 9 when it is desired to drive the rotary table 3. A driving rope or cable 12 passes around the driving wheel 8 and around the driven wheel 13 on the rotary table. Said driving and driven wheels 8 and 13 are provided with gripping means for engaging the rope or cable as it passes around the same, to give an effective grip sufficient for driving operation. The rotary drilling table has to

operate at relatively low speed and requires a powerful turning force to rotate it, such force being considerably beyond the transmitting capacity of any ordinary belt or frictional driving means. On this account it has been usual to drive the rotary drilling table by means of bevel gears which in turn are driven from a countershaft connected by belting to the engine shaft. Such intermediate connections are expensive and noisy and add greatly to the difficulty and cost of up-keep of the apparatus. By providing a single rope connection between the driving engine and the rotary drilling table, I have not only reduced the number of parts required, but avoid a very considerable source of difficulty in the operation of the rig. In order to provide the necessary grip between the wheel 8 and rope or cable 12, said wheel 8 is provided with an annular series of gripping jaws 15, arranged in pairs, each pair of jaws 15 being pivoted together as shown at 16 to form a toggle, said jaws having outwardly extending shanks 17 provided with rounded portions 18 engaging in rounded sockets 19 in flanges or annular shoulders 20 and 21 on the wheel. To facilitate assemblage of the jaws, annular flange 21 is made removable and held in position by bolts 22. The jaws 15 are provided with opposing faces 23 which are inwardly convergent and adapted to tightly grip the rope or cable 12 when said jaws are pressed toward the center of the wheel by the tension of the cable. Stop means 24 on one of the jaws engages with a stop means 25 on the hub 26 of the wheel 8 to limit the inward movement of the jaws so that they will not bite too tightly into the cable.

The wheel 13 on the rotary table may be formed with gripping jaws 28 and 29 arranged in pairs, said jaws being similar in construction and operation to the gripping jaws 15 aforesaid, and being provided with inwardly convergent opposing faces 30 adapted to grip the cable. In the case of this wheel 13, however, the pair of gripping jaws extend vertically and in order to facilitate the freeing of the jaws from the cable as they leave the cable, the lower jaws 29 are provided with weighted portions 32 tending to swing the pair of jaws outwardly or away from the center of the wheel 13 so as to open up or separate the corresponding faces 30 of the jaws. This rotary table may be mounted on roller bearings 34 and pro-

vided with an outwardly extending flange 35 over which extend brackets 36 on the base 38 to prevent any tipping motion of the table.

5 In the operation of the rotary table 3 by means of the transmission device above described the rotation of the driving wheel 8 causes the cable or rope 12 to be carried around in the groove of the drive wheel formed between the opposing faces of the gripping jaws and the pressure of the rope on these jaws tends to propel them inwardly and pinch them against the rope, thereby giving a tight grip on the rope, which is capable of transmitting many times the strain that could be transmitted by an ordinary frictional engagement. In a similar manner the rope, in passing around the wheel 13 on the rotary table 3, engages in the groove formed between the opposing faces of the gripping jaws on said wheel, and by its pressure on said jaws causes said jaws to grip the rope and transmit the rotative force to the rotary table. In consequence of this strong gripping action it is possible to drive the rotary table direct from the engine without interposition of the usual intermediate driving connections. I also provide in the drilling rig, for operating the various other rotative parts of the rig by transmission devices similar to those above described, thereby greatly reducing the number of parts required and simplifying the construction and operation of the rig. The shaft 40 for operating the walking beam is mounted on bearings 41 and is provided with a driving wheel 42 which is connected to a wheel 43 on the engine shaft 9 by rope 24, said wheels 42 and 43 being provided 40 with gripping jaws similar to those above described. A clutch 44 is provided for connecting wheel 43 to engine shaft 9. The wheel 42 also operates as a crank wheel being provided with a series of holes at 46 different distances from the center and adapted to receive a crank pin 48 on the pitman 49 connected at its upper end to the walking beam 50. Said shaft 40 may also carry the sand drum 51 which is loose on said shaft and is adapted to be connected thereto by a clutch 52. Another wheel 53 on shaft 40 is adapted to connect to said shaft by a clutch 54, and is connected by a rope 55 to a wheel 56 on a bull wheel 57, said 55 wheels 53 and 56 being provided with gripping jaws similar to those above described on the wheel 13.

The draw works indicated at 60, which may also be used in place of a calf wheel, is connected to the shaft 9 aforesaid by wire rope or cable 61 running over a wheel 62 on said shaft 9 and over wheel 63 on the shaft 64 for said draw works or calf wheel, said wheels 62 and 63 having gripping jaws 65 similar to those of wheel 13. A clutch 65 is

interposed between the shaft 9 and wheel 62 and the usual brake 66 is provided for the draw works or calf wheel.

By the above described construction and arrangement of the parts all the drilling operations whether by rotary or standard operation, can be performed conveniently and with minimum of obstruction due to the operating parts. The cost and weight of the rig are also materially reduced by the above described arrangement.

What I claim is:

1. In a drilling rig, the combination with the derrick, of an engine provided with a shaft, a plurality of wheels on said shaft, a clutch for connecting each of said wheels to said shaft, a rotary table provided with a wheel portion, a cable connecting said wheel portion of the rotary table with one of said wheels on the engine shaft, a second shaft, 70 a wheel on said second shaft, a cable connecting said wheel on said second shaft with the other wheel on said engine shaft, a plurality of clutches on said second shaft, 75 wheels connected to said second shaft by said clutches, a bull wheel and a draw works for the rig, wheels connected to said bull wheel and draw works respectively and cables engaging said last named wheels and said wheels connected by clutches to the 80 said second shaft.

2. In a drilling rig, the combination with the derrick, of an engine provided with a shaft, a wheel on said shaft, a clutch for connecting the said wheel to the shaft, a rotary table provided with a wheel portion, a cable connecting said wheel portion of the rotary table with said wheel, a second shaft provided with a plurality of clutches, 100 wheels on said second shaft and on the engine shaft, a clutch connecting said engine shaft and last named wheel thereon, a cable connecting said last named wheels, a sand drum on said second shaft connected to said shaft by one of said clutches, a bull wheel and a draw works for the rig and wheels connected to said bull wheel and draw works respectively, and cables engaging said last named wheels and two of the wheels on said second shaft, connected thereto by two of 105 said clutches thereon and engaging said last named cables to operate the bull wheel and draw works from said second shaft, each of 110 said cable-engaging wheels being provided with gripping means to forcibly grip the 115 said wheel.

3. In a drilling rig, the combination with the derrick, of an engine provided with a shaft, a wheel on said shaft, a clutch for connecting said wheel to the shaft, a second shaft provided with a wheel, a cable connecting said wheels, a sand drum on said second shaft, a clutch connecting said sand drum to said second shaft, a bull wheel and a draw works for the rig, each provided with 120 125 130

a driving wheel, cables engaging with said wheels of the bull wheel and draw works, wheels on said second shaft engaging said last named cables to drive the bull wheel and draw works from said second shaft, and clutches on said second shaft for connecting said shaft to said wheels for driving the bull wheel and draw works, each of said cable-engaging wheels being provided with

gripping means to forcibly grip the cable to the wheel.

In testimony whereof, I have hereunto set my hand at Los Angeles, California, this 13th day of June 1918.

ROSCOE W. STEPHENS.

In presence of—

ARTHUR P. KNIGHT,
LORA M. BOWERS.
